UNITED STATES PATENT OFFICE.

JOHN A. SOWELL AND ERNEST E. SOWELL, OF SACRAMENTO, CALIFORNIA.

GREASE-CUP.

1,219,599.

Specification of Letters Patent. Patented Mar. 20, 1917.

Application filed December 26, 1916. Serial No. 138,739.

To all whom it may concern:

Be it known that we, JOHN A. SOWELL and ERNEST E. SOWELL, citizens of the United States, residing at Sacramento, in the county of Sacramento, State of California, have invented certain new and useful Improvements in Grease-Cups; and we do declare the following to be a full, clear, and exact description of the same, reference being had to the accompanying drawings, and to the characters of reference marked thereon, which form a part of this application.

This invention relates to improvements in grease cups used for lubricating all kinds of machinery and other wearing parts. The object of the invention is to invent a cup of marked simplicity and one which will eliminate the possibility of the grease oozing from the inside to the outside of the cup when the follower is advanced against the same. The further object is to provide a ribbed guide for the follower which will hold the follower in positive position and cause it to act through the length of the grease cup in a firm and positive manner. In addition to this object the still further aim of the invention is to provide a simple and effective means for filling the grease cup when empty without the necessity of removing or replacing any of its parts. In the grease cups now commonly in use it is necessary first to remove some of the working parts before the cup can be filled and when this is done it is often hard to replace the same for various reasons, especially when the grease cup is placed in some inaccessible place on the machinery. Also in our improved grease cup the driven worm for the follower is positioned so as to make its movement positive and the same is also continuously held to true position centrally of the grease cup.

A further object of the invention is to produce a simple and inexpensive device and yet one which will be exceedingly effective for the purposes for which it is designed.

These objects we accomplish by means of such structure and relative arrangement of parts as will fully appear by a perusal of the following specification and claims.

In the drawings similar characters of ref-

erence indicate corresponding parts in the several views.

Figure 1 is a vertical sectional view of the grease cup.

Fig. 2 is a top plan view of the cover of the grease cup with the operating handle removed.

Fig. 3 is a plan view of the adjustable cover carried by the follower.

Fig. 4 is a transverse sectional view of the cup showing the follower in position with the cover of the follower removed.

Referring now more particularly to the characters of reference on the drawings, the numeral 1 designates the body of the casing of the cup which is substantially cylindrical in cross section and is provided at its lower end with a removable cap 2 threaded therein, such cap having an outlet 3 provided with threads 4 whereby the cup may be suitably fastened in the part to be lubricated. On the upper end of the casing 1 is a removable cap 5, threaded therein and provided with a central orifice 6.

The numeral 7 designates the operating handle of the grease cup provided with a shank 8, turnable in the orifice 6 and held in position therein by means of a flange 9 bearing against the under side of the cap 5. Extending below the flange 9 is an operating worm 10 which terminates at its lower end in a tapered point 11, turnable and mounted in a guide member 12 extending transversely across the lower end of the casing 1.

Screwed and mounted upon the worm 10 is the follower 13. This follower is provided in its circumference with V shaped incisions 14 which are guided from like shaped ribs 15 pressed into the side walls of the casing 1. This guide holds the follower 13 in positive position and causes its movement through casement 1 to be positive and firm. This follower 13 is of course provided with a suitable washer as at 16 in order to prevent any of the grease oozing from the under side to the upper side of the said follower.

Mounted on the upper side of the follower 13 is a cover disk 17 provided with two guide grooves 18 through which appear small set screws 19. Said screws are fastened in the follower 13. These said screws 19 hold the

disk 17 in position on the follower 13 and likewise limit the rotary movement of the disk 17 with respect to the said follower 13. This disk 17 is cut out at 20 to allow the 5 same to have the rotary movement relative to ribs 15. The follower 13 is provided with an orifice or opening 21 extending through from its upper to its lower sides and in disk 17 is a small opening 22 adapted to be moved 10 in or out of register 21 as the disk 17 is rotated to the extent of its movement as fixed by the guides 18. In the cap 5 is an elongated slot 23 disposed directly above the normal position of the openings 21 and 22. 15 On the disk 17 is a small vertical pin 24 which when the follower is at its uppermost position projects through the slot 23. By means of this pin the disk 17 can therefore be moved from the outside of the cap 5 to 20 bring the pin 24 in and out to register with the opening 21.

When the grease cup is empty the handle 7 is operated to move the follower 13 to its uppermost position. This advances the pin 24 through the slot 23. This pin 24 is then used to move the disk 17 to bring the openings 22 and 21 to register with each other. This then opens communication from the outside of the grease cup through the openings 23—22 and 21 to the inside of the grease cup. Thereupon the grease cup can be filled with grease by means of inserting the discharge nozzle of a grease gun through the registered openings. When the cup is filled 35 the pin 24 can then be used to turn the disk 17 to move the opening 22 out of register with the opening 21 whereby the disk 17 will form a normal closure for the opening 21 and prevent any of the grease from backing 40 through the same when the follower is advanced.

With the operating of the handle 7 the operated worm 10 is then rotated to advance the follower 13 on the same and force 45 the grease around the sides of the guide 12 whereupon the cup can again be refilled in the manner indicated above.

From the foregoing description it will be readily seen that we have produced such a 50 device as substantially fulfills the object of the invention as set forth herein.

Copies of this patent may be obtained for five cents each, by addressing the "Commissioner of Patents, Washington, D. C."

While this specification sets forth in detail the present and preferred construction of the device, still in practice such deviations from such detail may be resorted to as 55 do not form a departure from the spirit of the invention, as defined by the appended claims.

Having thus described our invention what we claim as new and useful and desire to secure by Letters Patent is:

1. A grease cup comprising a casing provided with an outlet from the bottom and an operating worm fixed for rotary motion on the top, a follower on the worm, and means 60 for filling the cup with grease without removing any of the parts thereof, such means comprising an opening through the casing and an opening through the follower, such openings being arranged to be brought into 65 communication with each other when the cup is filled and such communication shut off when the cup is in operation.

2. A grease cup comprising a casing and follower mounted for movement within the 75 casing and provided with an orifice, a disk mounted on the follower arranged to normally close such orifice, such disk being provided with an orifice arranged to be brought into register with the first named orifice, and 80 an opening in the casing body adapted to register with both of these first named orifices when they register with each other.

3. A grease cup comprising a casing and a follower mounted for movement therein 85 and provided with an orifice, a disk mounted on the follower and arranged to form a normal closure for such orifice, such disk being provided with an orifice arranged to be brought into register with the first named 90 orifice, such casing being provided with an orifice arranged to register with both of the first named orifices when they are in register with each other, and a pin on the disk adapted to project through the orifice in the casing whereby the same may be used to move 95 said disk.

In testimony whereof we affix our signatures.

JOHN A. SOWELL.
ERNEST E. SOWELL.
